UNITED STATES PATENT OFFICE.

JACOB W. LATTIG, OF WEST BETHLEHEM, AND CHARLES LANE GOODRUM, OF PHILADELPHIA, PENNSYLVANIA, ASSIGNORS TO EASTERN TELEPHONE MANUFACTURING COMPANY, OF WESTCHESTER, PENNSYLVANIA, A CORPORATION OF PENNSYLVANIA.

TWO-WIRE MULTIPLE TELEPHONE SYSTEM.

SPECIFICATION forming part of Letters Patent No. 769,701, dated September 13, 1904.

Application filed June 6, 1903. Serial No. 160,323. (No model.)

To all whom it may concern:

Be it known that we, JACOB W. LATTIG, residing in West Bethlehem, county of Lehigh, and CHARLES LANE GOODRUM, residing in

5 Philadelphia, county of Philadelphia, State of Pennsylvania, citizens of the United States, have jointly invented a new and useful Two-Wire Multiple Telephone System, of which the following is a specification.

10 Our invention relates to telephone-exchange systems, and particularly to those in which a common battery or other source of current-supply is employed for the purpose of furnishing energy for both transmitters and signals. We have described in a companion application hereto, executed of even date herewith, filed June 6, 1903, Serial No. 160,322, a system of this character in which metallic circuits are employed and but two contacts are 15 required in each spring-jack and on each co-operating plug in the central office. In that system polarized relays are employed to control the line-signals, and similar polarized relays are connected to the cord-circuits to control the supervisory signals. The benefits derivable from a two-wire multiple system are 20 fully set forth in said application, comprising, among others, the advantage of reduced size in multiple-jack panels, simplicity of wiring, reduction in size of cable and relay-racks, and 25 general economies, as well as a distinct gain in directness and simplicity of operation.

Our present invention is in the nature of an improvement upon the system set forth in our 30 application referred to; and it consists principally in certain improved arrangements of relays for the supervisory circuits whereby the polarity feature is eliminated, certainty of operation is assured, and other advantages are 35 gained which will be sufficiently evident from the description and claims.

In carrying out our invention we may use, and preferably do use, a polar relay for the line-signal, connected between one side of the 40 line and an intermediate point between the terminals of the main battery, together with

connections from one terminal to the corresponding side of the cord-circuit and from the other terminal to the other side of line, the potential difference on the cord side—as referred 50 to the “intermediate bus”—being higher than that on the line side. The effect of this is to produce a local circuit when a plug is inserted, having a reversed direction of current to restore the line-signal. In our other 55 application referred to, as well as in our Patent No. 722,637, issued to us March 10, 1903, we have also described polar relays in the cord to control the supervisory signals, and included in this local circuit when a plug is inserted. Current to the intermediate bus through the local circuit would light the supervisory lamp; but when a subscriber answered this would be reversed to extinguish the same. In the present case we use two 60 neutral relays, one of high and one of low resistance or number of effective turns in the winding, the low relay shunting the high relay when a large current passes to retire the signal, this occurring when a subscriber 65 answers, and thereby puts his line in shunt of the high-resistance line-signal. When a small current passes in the local circuit the high relay only becomes operatively energized to light the supervisory lamp, this occurring 70 when the line is open at the subscriber's station. Thus we are enabled to attain, with differences in resistance to utilize the differences in current strength, similar results to those attained by the use of polarities. 75

Our invention is illustrated in the accompanying drawing, wherein the figure is a diagram of a system, showing two subscribers' stations A and B, connected to a central office containing suitable connective apparatus. 80

Referring to the drawing, the substations A and B are connected to the central office by the line-wires 1 2 and 3 4, respectively. These stations are equipped with the usual transmitters T T', receivers R R', ringers Q Q', 85 condensers C C', and switch-hooks H H'. These do not form part of our present inven-

tion and may be of any suitable type to operate on central-energy metallic circuits. At the central office the lines are provided with terminal spring-jacks J and J', respectively, 5 each of these jacks consisting, essentially, of a spring and a sleeve only, the former lettered j and the latter j' . From the spring side of the line 1 it is connected through impedance-coil I to bus-bar 5, and the same is true of 10 the spring side of the other line, 3. The sides 2 and 4 of the respective lines are connected through the windings of polarized relays L and L' to the bus-bar 6. Each of these polarized relays is fitted with an armature normally drawn by the force of a suitable retractile spring, aided by the permanent magnetism of the field, into position to break a local circuit 8 or 9, containing a battery m or m' and a signal-lamp l or l' . When an armature of one of these relays is thrown over by 15 current of proper direction in the coil thereof, it closes the local circuit and lights the lamp therein. Coöperating with the spring-jacks J and J' in making connections between the lines are provided plugs P and P', connected 20 by cord conductors 18 19 20 21, inductively continuous, but conductively discontinuous by reason of the inclusion therein of the condensers C² C². Each plug has tip and sleeve 25 contacts p and p' , adapted to coöperate with the springs j and the sleeves j' of the jacks in 30 making connections. Across the conductors 18 and 20 the operator's telephone set O is adapted to be bridged by the listening-key K 35 when the latter is depressed. This key and the telephone set we have indicated conventionally in diagram only; but it is to be understood that all the required connections for 40 current-supply, tests, &c., are made thereto in practice, not being illustrated in detail herein because they form no part of this invention and may be varied at will. In the 45 conductors 19 and 21 are included the double contacts of the ringing-key K', which when operated serves to separate the plug P' from the other plug, P, and connects the conductor ends thereof to the circuit 17 of the ringing-generator G. This also is conventionally shown. Associated with the plugs are two 50 supervisory signals l^2 and l^3 , included in the local circuits 10 and 11, together with suitable batteries m^2 and m^3 , the local circuits being normally open and controlled by the armatures of relays L² and L³, respectively. 55 The relay L² is connected on one side by wire 15 to the conductor 18 of the cord, and on the other side to the windings of a second relay L⁴ and thence by wires 12 and 14 to the bus-bar 7. Similarly, the relay L³ is connected 60 on one side by wire 16 to cord conductor 19 and on the other to relay L⁵ and thence by wires 13 and 14 to the same bus 7. The relay L⁴, by its armature a^4 , controls the continuity of a short circuit or shunt 24 25 around the 65 relay L², extending from wire 15 to wire 23.

The relay L⁵, by its armature a^5 , controls the continuity of a shunt 24 25 around relay L³, extending from wire 16 to wire 26. Relays L and L' are wound to have a resistance of approximately one thousand five hundred ohms 70 each and to offer a high impedance to the passage of voice or other high-frequency currents. Relays L² and L³ are wound to about one thousand ohms each, and relays L⁴ and L⁵ are of a special design, which will now be noticed. 75 Each of these relays L⁴ and L⁵ has a point of division in its windings. The total resistance of the entire winding on each is about equal to that of the winding of coil I, or approximately three hundred and fifty ohms; 80 but that portion of its windings next to the armature end of the core or cores is of only about fifty ohms resistance, the division being made in such manner as to make this the only portion effective in attracting the armature. 85 This may be done in various ways. We have chosen for illustration an arrangement in which a core extension a^{40} , of soft iron, is brought out between the two portions of the relay-winding and extended down so as to 90 pivot the armature to it, thus limiting the effective magnetic circuit to the armature, the core extension, and that portion of the core between them. The entire winding is effective in increasing the resistance and impedance 95 of the magnet, however. The main battery used with these coils is shown conventionally, at M M'. It is in two divisions, the lower one, M', of, say, fifteen cells, giving approximately two volts each, and the upper one of, 100 say, ten cells, giving two volts each, twenty-five cells in all, giving a total voltage between bus-bars 5 and 7 of fifty volts. These voltages and also the resistances given may be departed from without altering the invention; 105 but we give those we have found suitable.

The operation of our system so described is as follows: Suppose subscriber A calls by removing his receiver R from the hook H. The line becomes closed for calling-current from the main battery M by the following path: battery M, bus-bar 6, relay L, line-wire 2, hook H, transmitter T and receiver R, line-wire 1, coil I, and bus-bar 5 to battery. The relay L becomes energized by the current in this circuit and throws over its armature, closing the local circuit 8 and lighting the lamp l. The operator perceiving the signal inserts the answering-plug P in the answering-jack J, and after depressing the key K asks the 110 number wanted. When the plug is inserted, a circuit is closed for battery M', as follows: battery M', bus-bar 7, wire 14, coils L⁴ and L⁵, cord conductor 18, plug-contact p' , jack-thimble j' , line-wire 2, and by one path back 115 through relay L to bus-bar 6, by the other path out over the line, through the subscriber's apparatus, as before, back by line-wire 1, through coil I to bus-bar 5 and battery M to battery M'. The battery M and the battery M' 120

125

130

are thus seen to be connected oppositely to relay L_1 , and as the potential between bus-bars 6 and 7 is higher than that between bus-bars 6 and 5 the former prevails and the current due to the resultant potential difference at the terminals of relay L_1 is in a direction to throw back its armature to its normal open point, as shown, in which it is aided by the spring. The current from both divisions M and M' of the battery is thrown on the line to supply the subscriber's transmitter, which is preferably of the high-resistance central-energy type now coming into general use. If the subscriber should return his telephone-receiver to its hook after calling, the effect on the supervisory signals would be as follows: Current from battery M' only circulating in the local circuit 14 L^4 L^2 18 2 L_6 is so attenuated by reason of the high resistance of relays L_1 and L^2 and there are so few effective turns on the active core end of relay L^4 that the armature a^4 of the latter is not attracted and relay L_1 does not attract its armature effectively, because the current is in the wrong direction; but relay L^2 has a sufficient number of turns to be effective even with this attenuated current, and it attracts its armature a^2 to close the local circuit 10, which lights the supervisory lamp L^2 , indicating that the subscriber has "hung up." On the other hand, if, according to the usual procedure, subscriber A keeps his receiver off the hook until he is through talking the above current is supplemented as regards the path 14 12 L^1 L^2 15 18 p' j' 2 by the additional current permitted to flow to the substation, or, to put it in other words, the current is increased by shunting the resistance of relay L_1 . This increased current is sufficient to effectively energize the core of relay L^4 , and it attracts its armature a^4 , short-circuiting the magnet L^2 , which thereupon lets its armature remain retracted, leaving the lamp L^2 dark. Having ascertained the number wanted, the operator inserts the plug P' into a multiple jack of the line, which we will suppose to be that of station B. (She precedes this insertion by a test, description of which is omitted.) Depression of the key K' then sends ringing-current to line 3 4 and calls subscriber B by agitating his ringer Q' . In inserting plug P' the operator has closed the circuit of battery M' by way of 7 14 13 L^5 26 L^3 16 19 p' j' 4 L_1 6, the subscriber's line 3 4 remaining open at condenser C' . Current in this path is attenuated by the resistance of relays L^3 and L^5 and fails to energize relays L^3 , but does energize relay L^5 to attract the armature a^5 and light lamp L^5 in supervisory circuit 11. This lamp remains lighted until the called subscriber answers. When he takes down his receiver from the hook, the path to his station is closed for direct current and shunts the resistance of relay L_1 . The increased current in L^5 due to this is sufficient to attract armature a^5 , whereupon a

shunt 24 25 is closed, as previously described, around relay L^3 , and the latter releases its armature-extinguishing lamp L^3 . This signalizes to the operator that the subscriber has answered. Conversation proceeds with current flowing to keep both supervisorys dark, and it will be noted that this current is not waste, but serves to keep the transmitters at the substations supplied with energy. The function of the additional resistance and impedance of magnet L^5 now appears, for it serves, in conjunction with coil I' , as L^4 in conjunction with I , to choke speech-waves out from the battery bus-bars. Having finished their conversation, when A or B, or either of them, hang up their receivers the corresponding relays L^4 and L^5 weaken and release their armatures, breaking the short circuits around the supervisory relays L^2 and L^3 and again lighting both lamps L^2 and L^3 , or either one of them, as the case may be.

Having thus described our invention, what we claim, and desire to secure by Letters Patent, is—

1. In a telephone-exchange system, subscribers' lines, operators' connective circuits, a common source of current, a high-resistance line-relay in each line, a low-resistance supervisory relay in connection with each connective circuit, a circuit completed when a connective circuit is connected to a line, which comprises the supervisory relay the line-relay and a portion of the source or the whole thereof, in series, and means under the control of the subscriber to open and close his line in the use of his telephone, said line constituting a shunt for current through the supervisory relay around the line-relay, whereby the supervisory relay is controlled, substantially as described. 105

2. In a telephone-exchange system, subscribers' lines, operators' cord-circuits, spring-jacks for the lines and plugs coöperating therewith for the cords, a source of current, a high resistance in each line between the spring-jack and the source of current, a supervisory relay-magnet connected between each cord and the source and adapted to be brought into series with line resistance and source when a plug of its cord is inserted in a jack, together with means at each subscriber's station to close a shunt-path through the line around the line-resistance to control the supervisory relay-magnets, substantially as described. 110

3. In a telephone-exchange system, a subscriber's line, an operator's cord-circuit, jacks for the line and a plug for the cord, a source of current, a high-resistance connection from the source to the jacks, a low-wound relay and a high-wound relay in series connected from the other side of the source to the cord, means whereby the high-wound relay may control a signal and the low-wound relay may control a shunt around the high-wound relay, together with means under the control of the 125

subscriber to close his line-circuit to furnish a path of comparatively low resistance around the normal line connection from the source, whereby the high-wound cord-relay may be shunted during a connection and its signal undisplayed, but the low-wound relay may be deenergized to restore the same and permit it to display its signal at the conclusion of a conversation and when the line-circuit is broken, substantially as described.

4. In a telephone-exchange system, a subscriber's line with a terminal jack, a cord-circuit with a terminal plug, a divided source of energy having intermediate and terminal bus connections, a connection from the jack through a high resistance to the intermediate bus, a connection from the cord through a low-wound non-sensitive supervisory relay to one terminal bus, and means controlled by the subscriber to close a branch circuit from the jack through his line to the other terminal bus, whereby on the insertion of a plug the cord-relay will not be energized, whereon the closure of the line by the subscriber it will be energized, substantially as described.

5. In a telephone-exchange system, a signal-magnet comprising a divided winding, a continuous core for both divisions of the winding, an armature at one end of the core and an extension of the core from the point of division between the coils to the armature, together with suitable connections and sources of current, whereby for signaling purposes a portion of the winding only will be effective, but in developing self-inductance in the circuit the entire winding will be effective, substantially as described.

6. In a telephone-exchange system, a subscriber's line and a terminal jack therefor, a cord-circuit and a terminal plug therefor to

cooperate with the jack, a source of current, a high-resistance connection from the source of current to the line and jack, a sensitive relay controlling a signal, and a non-sensitive relay controlling the sensitive relay, both being connected from the source to the cord, together with means controlled by the subscriber to close through his line a path of relatively low resistance from the jack to the source, substantially as described.

7. In a telephone-exchange system, a subscriber's metallic circuit, a high-resistance signal-magnet connected to one limb thereof and an impedance-coil to the other, a divided battery having an intermediate terminal and two end terminals of unequal potential difference with the intermediate terminal, connections from the intermediate terminal to the high-resistance signal-magnet and from the low-potential end terminal to the impedance-cord, a cord-circuit adapted to be brought into connection with the line, a supervisory signal, a high-resistance relay controlling the same, a low-resistance relay having few effective turns on its core controlling a shunt about the high-resistance relay, and a connection from the cord through both relays in series to the high-potential end terminal of the battery, together with means at the subscriber's station to determine the continuity of the line, substantially as described.

In witness whereof we have hereunto signed our names in the presence of two subscribing witnesses.
